FASTENING MEANS FOR FURNITURE LEGS,
FRAMES, AND TOPS

John B. Barnes, Jr., Des Moines, Iowa

Application October 20, 1951, Serial No. 252,250

5 Claims. (Cl. 311—110)

1

My invention relates to the art of detachably joining two or more pieces of furniture or the like.

Furniture, among many other commodities, is today sometimes sold in a knocked-down form for assembly by the user. Such pieces usually require some tool such as a screw driver or hammer for assembling and are finally glued so that once completed, it is not intended that they be taken apart. Obviously, such prefabricated furniture is not usable until it has been assembled and time permitted for the glue to set, since the gluing is an important step in making the joints rigid.

With these matters in mind, I have invented a new and novel fastening means for securing furniture and like items that makes it possible for prefabricated furniture to be quickly and easily assembled without the use of any tools.

Other objects of my invention are to provide a fastening means of the above class by which furniture and the like can be rigidly assembled without any form of glue, screws or bolts, is immediately usable upon being assembled, and requires no special skill in assembling or disassembling.

Still a further object of this invention is to provide a joint or fastening means for furniture as characterized above which is easily releasable without tools so that an assembled unit can be knocked down and formed into a small compact unit for storage or transportation.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of a stool assembled by means of my new joint.

Fig. 2 is a reduced perspective view showing the stool of Fig. 1 disassembled and arranged into compact form for storage or transporting.

Fig. 3 is a top view of one corner of the stool of Fig. 1 with a portion cut away and a portion in section to more fully illustrate its construction.

Fig. 4 is an exploded view of one corner section of the stool in Fig. 1.

Fig. 5 is an enlarged view of the securing dowel used in this joint.

Fig. 6 is a cross-sectional view of this joint taken on the line 6—6 of Fig. 3, and

2

Fig. 7 is a fragmentary exploded view showing a corner post or leg and one of the side rails securable thereto.

Referring to the drawings I have selected an ordinary type four legged stool 10 to illustrate my new fastening means. This joint will be described for only one corner leg section but it will be appreciated that the construction pointed out is duplicated for each of the legs. Obviously, a lesser or greater number of legs or posts may be employed in any specific unit without departing from the principle of my invention.

It is also to be observed that while I have preferably selected a piece of furniture by which to describe my invention, it will become apparent that the principle I have conceived can without change be adapted to toys and the like not only for use in assembling a toy, but to provide a source of training for a child in the assembly and disassembly of the same.

The stool 10 consists of a plurality of like legs or post members 12, a number of side rails or supports 14 equal to the number of legs 10, a top or seat 16, and if desired, corner braces 18. These are usual elements in a stool or like piece of furniture and my invention resides in a unique means for detachably securing them together into the completed unit. Various joint means such as mortise joints, half lap joints, butt joints and the like are all well known in assembling furniture and all require some auxiliary securing means such as nails, screws, bolts, glue and the like. In their respective uses, these joints are intended to be permanent and if they reach a point where they can be easily taken apart, their function has been destroyed and repairs are necessary. My invention, on the other hand, is designed to produce a rigid joint means and yet may be quickly disassembled if desired.

A vertical groove or slot or mortise socket 20 is formed in the upper portion of each leg 12 on each side to which a rail or support 14 will be secured in the particular article of furniture or the like to be assembled. This slot 20 communicates with the top of the leg 12 and extends downwardly on the leg a distance equal to the width of the rail 14 to be used. One end of the rail 14 is provided with a tongue or tenon 22 that is adapted to be frictionally arranged within the slot 20 as will be apparent from Figs. 4 and 7. In this position, the top of the rail 14 will be on the same horizontal plane as the top of the leg 12 and the bottom of the slot 20 serves as a stop means to limit any downward movement of the tongue 22 within the socket 20. Preferably, I

3

have made the groove 20 of dove-tail shape and the tenon 22 is flared or dove-tailed so that the well known dove-tail interlocking joint is formed. With such dove-tailing, the rail 14 will be arranged by sliding the same downwardly into the mortise socket 20. In this position it is apparent that the rail and leg can be pulled apart in one direction only and that is by moving the tenon 22 upwardly in the slot 20. As pointed out heretofore, each leg is secured to its respective rail or rails in the same manner just described and thus secured a basic frame structure is created. To this is added a seat 16 which is mounted on the top of the frame as shown in Fig. 1. At a point on the seat 16 that will be in engagement with the top of a leg 12, a transverse hole 24 is made which is countersunk at the top as shown at 26 in Fig. 4. A shallow vertical hole 28 is made in the top of the leg 12 so that when the seat 16 is in place as shown, the opening 24 and hole 28 will register. A dowel 30 provided with an enlarged head 32 and a transverse opening 34 in its lower shank portion is frictionally mounted through the hole 24 and into the hole 28 so that the dowel head 32 seats in the countersunk portion 26 of the hole 24. A horizontal opening 36 extends through the top portion of the leg to register with the hole 28 and the hole 34 in the bottom of the dowel 30. A small tapered dowel pin 38 is positioned in the opening 36 (Fig. 4) so that it passes through the hole 34 into the dowel 30 and locks the same in position. The length of the dowel pin 38 should preferably correspond to the width of the leg so that it will be flush with opposite sides thereof when in place. When placing the dowel pin 38, the tapered end is first inserted and thus it can be easily manually pushed into place.

It will be observed that for most uses the pin 38 will be rather small and since the taper may not be readily susceptible to the eye, I have marked the tapered end 40 in some identifiable manner such as by coloring.

The seat 16 when mounted as described locks the rails 14 against any accidental upward movement and when all corners or leg sections are assembled as described, the completed stool, chair, or the like is ready for use.

By way of adding strength to any assembled unit, I have shown a corner brace member 18 which is arranged in relation to each leg as shown by the broken lines in Fig. 3. Each end of these braces 18 is beveled at a forty-five degree angle as at 42 so they will fit flush to the respective rails 14 in a well known manner. However, on the upper portion of each end 42 of the braces (preferably about the upper one-half thereof) I provide the flared tenon or tongue 44 that extend perpendicularly from the beveled edges 42. On the inner side of each rail 14 near each tenon 22, a flared groove or dove-tail socket 46 is formed that communicates with the top of the rail and extends downwardly for a distance equal to the length of the brace tenon 44. In using these braces 18 they are set in place prior to securing the seat 16 and this is accomplished merely by frictionally sliding the braced tenons 44 downwardly in the rail sockets 46. In doing this, the bottom of the sockets 46 will serve as a stop means to limit the downward movement of the braces 18 and the braces when in place, should have their top edges on the same horizontal plane as the top edges of the rail. Preferably the braces will be of the same width and thickness as the rails so that both their top and bottom

edges will be on the same respective planes. It will be observed that the braces can be removed only in one direction, namely upwardly, the same as the rails, so that when the seat is in place as described, it acts to lock them against accidental release.

No screws, bolts or glue is necessary or required in assembling an article by use of my joint means as the dowel 30 and dowel pin 38 will lock the seat in place and the seat in turn will serve to lock all other rails and braces used to make a rigid assembly.

To disassemble the stool shown in Fig. 1 or any other article embodying my joint means, the dowel pin 38 is first removed and the other members manually separated in inverse order to that of their assembly. Preferably a pencil or other pointed object can be used to push the dowel pin 38 out far enough to manually grasp it and in doing this, the dowel end 40 having some identifying indicia thereon will indicate the correct end against which the pencil or the like will be pushed.

From the above disclosure, it will be apparent that the ease of assembly and disassembly of a piece of furniture by my new joint or fastening means has many advantages. From the standpoint of the user, he can of course quickly set up an immediately usable item. No tools or glue are required nor is any special skill necessary and probably of special advantage is the fact that in event the use of the particular article is no longer required or in case of moving from one house or building or city to another, each unit embodying my invention can quickly be disassembled and formed into a compact unit (Fig. 2) for storage or transporting and it is obvious that a much smaller space will suffice for an article arranged as shown in Fig. 2 than for the same article completely assembled.

It is intended that the uses for my fastening means are not to be limited to standard articles of furniture. As for example, it is well known that furniture in miniature is made for use by children and in this respect my invention may be embodied not only for its practical application in shipping, using and storing the same, but for its educational value and training for the child in doing the actual assembly and disassembly himself.

Some changes may be made in the construction and arrangement of my fastening means for securing furniture and like items without departing from the real spirit and purpose of my invention, and it is my intention to cover by my claims, any modified forms of structure or use of mechanical equivalents which may be reasonably included within their scope.

I claim:

1. A means for releasably fastening the several parts of an article of furniture such as support members or legs, rails and a top member, without requiring nails, screws, plates or a bonding agent, comprising, said support members being provided with grooves communicating with the tops thereof and terminating at a point intermediate the ends thereof, rails, tenons on the ends of said rails, said support members interconnected by said rails with the tenons slideable into and out of said grooves respectively from the top only, said top member arranged on said rails and said support members, dowels removably connecting said top member to each respective support member, and dowels in each support member removably interlocking with said

first mentioned dowels respectively whereby said top member is locked in place and becomes the key locking element against the removal of all other parts.

2. A furniture fastening means as defined in claim 1 wherein the removal of said top member only makes all other parts releasable from each other.

3. A means for releasably fastening the several parts of an article of furniture such as support members or legs, rails and a top member, without requiring nails, screws, plates or a bonding agent, comprising, said support members being provided with grooves communicating with the tops thereof and terminating at a point intermediate the ends thereof, rails, tenons on the ends of said rails, said support members interconnected by said rails with the tenons slidable into and out of said grooves respectively from the top only, said top member arranged on said rails and said support members, dowels removably connecting said top member to each respective support member and tapered dowels insertable and removable from one side only of each support member respectively removably interlocking with said first mentioned dowels respectively whereby said top member is locked in place and becomes the key locking element against the removal of all other parts.

4. A means for releasably fastening the several parts of an article of furniture such as support members or legs, rails and a top member, without requiring nails, screws, plates or a bonding agent, comprising, said support members being provided with grooves communicating with the tops thereof and terminating at a point intermediate the ends thereof, rails, tenons on the ends of said rails, said support members interconnected by said rails with the tenons slidable into and out of said grooves respectively from the top only, said top member arranged on said rails and said support members, dowels removably connecting said top member to each respective support member, said dowels insertable into and removable from said top member from one side only, and dowels in each support member

removably interlocking with said first mentioned dowels respectively whereby said top member is locked in place and becomes the key locking element against the removal of all other parts.

5. A means for releasably fastening the several parts of an article of furniture such as support members or legs, rails and a top member, without requiring nails, screws, plates or a bonding agent, comprising, said support members being provided with grooves communicating with the top thereof and terminating at a point intermediate the ends thereof, rails, tenons on the ends of said rails, said support members interconnected by said rails with the tenons slidable into and out of said grooves respectively from the top only, said top member arranged on said rails and said support members, dowels removably connecting said top member to each respective support member, said dowels insertable into and removable from said top member from one side only, and tapered dowels insertable and removable from one side only of each support member respectively removably interlocking with said first mentioned dowels respectively whereby said top member is locked in place and becomes the key locking element against the removal of all other parts.
